ATTORNEY.

UNITED STATES PATENT OFFICE.

HENRY V. STEVENS, OF EMPORIA, KANSAS.

SECTIONAL FLUE EXPANDER.

Application filed May 26, 1920. Serial No. 324,364.

To all whom it may concern:

Be it known that I, HENRY V. STEVENS, a citizen of the United States, residing at Emporia, in the county of Lyon and State 5 of Kansas, have invented certain new and useful Improvements in Sectional Flue Expanders, of which the following is a specification.

This invention relates to flue expanders 10 and has especial reference to the production of a simple and efficient expander which is so constructed as to prevent the crushing of the flue head when expanding the flue and setting the head outward.

15 Other objects and advantages of the present invention will appear throughout the specification and claim.

In the drawings:—

Fig. 1 is a longitudinal section through 20 the flue expander, a portion of the flue and boiler head, and

Fig. 2 is a side elevation of the flue expander.

By referring to the drawing, it will be 25 seen that 1 designates the flue within which is placed the sectional flue expander 2. The flue expander 2 is provided with a concaved channel 3 extending circumferentially around the flue expander between the shank 30 4 and the head 5 of the expander. This concave channel is located at a point where the bead 6 is formed at the end of the flue 1 and by having the concaved channel 3 so formed

in the flue expander 5, it will be seen that the flue head will be protected against breaking and crushing and in this way prevent the electric welded portion indicated by the numeral 7 from being broken or cracked away from the boiler head 8.

It should be understood that the flue expander may be made of any shape or size without departing from the spirit of the invention so long as the concaved recess or channel 3 is provided intermediate the shank portion 4 and the head 5. It should also be understood that other detailed mechanical changes may be involved without departing from the spirit of the invention so long as these changes fall within the scope of the appended claim.

50 I claim:—

A flue expander comprising a shank, an intermediate portion, and a head, said head being spaced from the shank by said intermediate portion, said intermediate portion 55 having a diameter smaller than the shank thereby forming a channel between the channel and the head, said channel being substantially concave for the purpose specified.

50 In testimony whereof I affix my signature 60 in presence of two witnesses.

HENRY V. STEVENS.
